UNITED STATES PATENT OFFICE.

WILLIAM E. UNDERWOOD, OF GAINESVILLE, TEXAS.

DESIGN FOR A SPUR-BODY.

SPECIFICATION forming part of Design No. 35,697, dated February 4, 1902.

Application filed May 27, 1901. Serial No. 62,174. Term of patent 7 years.

To all whom it may concern:

Be it known that I, WILLIAM E. UNDERWOOD, a citizen of the United States, residing at Gainesville, in the county of Cooke and 5 State of Texas, have invented and produced a new and original Design for a Spur-Body; and I do hereby declare the following to be a full, clear, and exact description of the invention, such as will enable others skilled in the 10 art to which it appertains to make and use the same, reference being had to the accompanying drawings, and to letters of reference marked thereon, which form a part of this specification.

15 Figure 1 is a plan view of a spur-body, showing my new design; and Fig. 2 is a side elevation of the same.

As shown in the drawings, the leading or material feature of my design consists of the 20 peculiarly-shaped upturned arms formed at the rear extremities of the U-shaped body of the spur, said upturned arms being inclined at the front in a substantially straight line lying at an obtuse angle to the top of the said

spur-body, the approximately straight line 25 gradually changing near the top of the arm to a curved line, which continues downward and forward to the lower line of the spur-body.

In said drawings, *a* is the U-shaped body. *b* are upturned arms at the rear of said body. 30 *c* is the upper outline of said body.

d represents the substantially straight forward end inclined lines of the arms *b*, *e* represents the curved lines at the top of said arms, and *f* represents the rearward continuations 35 of the curvatures which connect with the bottom or lower lines *g* of the spur-body.

What I claim as new is—

The design for a spur-body, substantially as herein shown and described. 40

In testimony that I claim the foregoing I have hereunto set my hand this 22d day of March, 1901.

WILLIAM E. UNDERWOOD.
